(57) **CLAIM**

The ornamental design for a fishing trap, as shown and described.

DESCRIPTION

FIG. 1 is a front perspective view of a fishing trap; FIG. 2 is a back perspective view of the fishing trap of FIG. 1; FIG. 3 is a bottom front perspective view of the fishing trap of FIG. 1; FIG. 4 is a bottom left perspective view of the fishing trap of FIG. 1; FIG. 5 is a front view of the fishing trap of FIG. 1; FIG. 6 is a back view of the fishing trap of FIG. 1; FIG. 7 is a left side view of the fishing trap of FIG. 1; FIG. 8 is a right side view of the fishing trap of FIG. 1; FIG. 9 is a top view of the fishing trap of FIG. 1; and, FIG. 10 is a bottom view of the fishing trap of FIG. 1.

The broken lines shown in the figures that are immediately adjacent to the shaded areas and define unshaded regions including the series of small circular openings on the bottom of the fishing trap in FIGS. 3, 4, and 10, represent the bounds of the claim. All other broken lines, including the features within broken line boundaries, are directed to environment. The broken lines form no part of the claimed design.
